(57) **CLAIM**

The ornamental design for a tool bit holder assembly as
shown and described.

DESCRIPTION

FIG. 1 is a perspective view of an embodiment of a tool bit
holder assembly in an open position including a cover
partially removed from around a tool holder;

FIG. 2 is a perspective view of an embodiment of the tool
bit holder assembly in a closed position including the cover
attached to the tool holder;

FIG. 3 is a side view of an embodiment of the tool bit holder
assembly in the closed position;

FIG. 4 is a perspective view of an embodiment of the tool
bit holder assembly in the closed position;

FIG. 5 is a top-down plan view of an embodiment of the tool
bit holder assembly;

FIG. 6 is a perspective view of an embodiment of the tool
bit holder assembly with the cover removed to depict details
of the tool holder;

FIG. 7 is a perspective view of an embodiment of the tool
bit holder assembly with the cover removed to depict details
of the tool holder with exemplary tool bits positioned at the
tool holder;

FIG. 8 is a side view of an embodiment of the tool bit holder
assembly with the cover removed to depict details of the tool
holder;

FIG. 9 is a side view of an embodiment of the tool bit holder
assembly with the cover removed to depict details of the tool
holder with exemplary tool bits positioned at the tool holder;

FIG. 10 is a perspective view of an embodiment of the tool
bit holder assembly with the cover removed to depict details
of the tool holder;

FIG. 11 is a top-down plan view of an embodiment of the
tool bit holder assembly with the cover removed to depict
details of the tool holder;

FIG. 12 is a perspective view of an embodiment of the tool
bit holder assembly with the cover removed to depict details
of the tool holder; and,

FIG. 13 is a bottom-up plan view of an embodiment of the
tool bit holder assembly with the cover removed to depict
details of the tool holder.

The broken lines illustrate portions of the design that form
no part of the claim.
